UNITED STATES PATENT OFFICE.

MARINE JOHNSON, OF ROSENDALE, WISCONSIN.

PUMP.

No. 832,734.

Specification of Letters Patent.

Patented Oct. 9, 1906.

Application filed May 11, 1905. Serial No. 259,862.

To all whom it may concern:

Be it known that I, MARINE JOHNSON, a citizen of the United States, residing at Rosendale, in the county of Fond du Lac and State of Wisconsin, have invented a new and useful Pump, of which the following is a specification.

This invention relates to pumps, more particularly to pumps adapted for transferring milk, cream, and like liquid substances from place to place, and has for its object to produce a simply-constructed and efficient device of this character whereby the liquid is caused to flow from one receptacle to another by the alternate compression and exhaustion of air and without permitting the liquid to come in contact with the air-actuating mechanism.

Another object of the invention is to produce a simply-constructed device of this character wherein all the parts are easily separable for thorough cleansing and held together by a single bail and set-screw.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of the advantages of this invention within the scope of the appended claim.

In the drawing the figure is a longitudinal sectional elevation of the device complete.

The improved device comprises a chamber 10, preferably cylindrical, with an integral closed bottom 31 and open at the top and with an integral lateral rim 20 at the open end. Depending from the closed bottom 31 is a smaller chamber 32, into the lower end of which the suction-pipe 11 leads and in the upper end of which a valve 15 is seated. The chamber 10 is provided with a closure 12, having a rim 33 depending within the open top of the chamber and with a flange 34 bearing over the extended rim 20, a flexible packing-ring

13 being disposed between the flange and rim, as shown. Depending from the closure 12 is a tubular member 14, with the lower end of the tubular member spaced from the upper end of the conduit 11. The valve 15 thus operates between the free end of the tubular member 14 and its seat, the tubular member thus serving as a stop to prevent the unseating of the valve when open.

Rising from the closure 12 is a smaller chamber 16, integral with the closure, which for the purpose of this description is referred to as the "valve-chamber" and is open at the outer end and provided with a detachable closure 17 and from which the discharge-conduit 18 leads. A valve 19 is seated in the upper end of the tubular member 14 and opens into the chamber 16. Engaging the rim 20 are the inwardly-extending ends 21 22 of a bail 23, the loop of the bail enlarged, as at 24, and having a threaded aperture for receiving a set-screw 25 for bearing upon the valve-chamber closure 17. A stem 26 extends from the lower end of the screw 25 through an aperture in the closure 17 and into the valve-chamber 16 to form a check to the valve 19 and preventing it from unseating when operated. An air-pipe 27 leads into the chamber 10 near the top and is connected at the other end to a suitable mechanism whereby air may be alternately compressed into and exhausted from the chamber 10. Any suitable device may be employed for thus actuating the air, such as a cylinder 28, having a plunger or piston 29 and piston-rod 30, the latter to be operated by any approved power.

By this simple construction it will be obvious that when the plunger 29 is drawn outwardly a "suction" will be produced in the conduit 11, which will open the valve 15 to cause the liquid to rise into the chamber 10, the amount being governed by the force of the suction and the length of the stroke of the plunger. Then at the return stroke of the plunger the compression of the air will instantly seat the valve 15 upon the intake 11 and force the liquid which has been drawn into the chamber 10 into the tubular member 14 and thence through valve 19, chamber 16, and discharge-conduit 18, and this action may be continued indefinitely or until the liquid has been all transferred. The capacity of the cylinder 28 is so proportioned relative to the chamber 10 that the upstroke of its piston 29 will not cause the liquid to

rise into the chamber high enough to overflow into the air-pipe 27 for obvious reasons. By this simple arrangement it will be noted that the liquid is caused to flow rapidly 5 through chamber 10 and its attachments without coming in contact with the piston 29, which produces the requisite pressure, but flows by an easy movement and without violent agitation or "churning" action, 10 which is very essential in handling milk, cream, and like delicate liquids.

The valves 15 and 19 being large and free 15 acting, the liquids are not crowded or compressed. Hence the particles are not separated or partially churned in passing through the apparatus, as so frequently occurs when moving milk by the ordinary pumps.

The milk is caused to move into the chamber 10 by the flexible and yielding atmospheric pressure upon the mass in the initial 20 receptacle and then forced into the final receptacle by a correspondingly - yielding means, the air-pressure above the mass in the chamber produced by the return stroke of the piston 29 thus securing the desired results with 25 the least possible agitation of the milk.

It will also be noted the device is readily 30 separable into its component parts for thorough cleansing at frequent intervals, which is so very essential with all apparatus with 35 which milk or similar easily-affected liquids come in contact.

The device will be found especially valuable in creameries and cheese-factories and 35 similar localities and may be constructed in

any required size or capacity and operated by any required power.

Having thus described the invention, what is claimed is—

In a pump, a chamber open at one end and 40 with an inlet at the closed end, an inlet-valve seated at the juncture of the inlet and chamber, a tubular member open at the ends and with a lateral flange intermediate the ends for bearing upon the open end of the chamber and forming a detachable closure to the same and maintaining the inner end of the tubular member spaced from the inlet-valve and preventing the displacement of the same, 45 said tubular member having a lateral discharge exteriorly of the closure-valve and an internal valve-seat adjacent to the lateral discharge, a valve upon said tubular-member-valve seat, a closure detachably disposed upon the outer end of said tubular member, 50 a yoke extending over said tubular-member closure and connected at the ends to said chamber, a clamp-screw operating through said yoke and bearing upon said closure, a pin extending from said screw through said closure and spaced at its free end from the tubular-member valve and preventing the displacement of the same.

In testimony that I claim the foregoing as my own I have hereto affixed my signature 55 in the presence of two witnesses.

MARINE JOHNSON.
